CLAIM

We claim the ornamental design for an absorbent article, as shown and described.

DESCRIPTION

FIG. 1 is a top view of an absorbent article.

FIG. 2 is a first side view of the absorbent article of FIG. 1.

FIG. 3 is a back view of the absorbent article of FIG. 1.

FIG. 4

is a second side view of the absorbent article of FIG. 1.

FIG. 5 is a first end view of the absorbent article of FIG. 1; and,

FIG. 6 is a second end view of the absorbent article of FIG. 1.

The broken lines shown in FIGS. 2 and 4-6 illustrate portions of the absorbent article that form no part of the claimed design.

1 Claim, 2 Drawing Sheets
